UNITED STATES PATENT OFFICE.

CARL A. WISS, OF FORT DODGE, IOWA.

CULTIVATOR.

Application filed September 30, 1924. Serial No. 740,804.

To all whom it may concern:

Be it known that I, CARL A. WISS, a citizen of the United States, residing at Fort Dodge, in the county of Webster and State 5 of Iowa, have invented certain new and useful Improvements in Cultivators, of which the following is a specification.

This invention appertains to cultivators and the primary object of the present invention is to provide a novel cultivator for cultivating the putting greens of golf courses and which is so constructed as to permit the easy operation thereof over the green.

Another object of the invention is to provide a putting green cultivator for golf courses embodying a wheeled supporting frame and a cylinder supporting a plurality of rows of cultivator teeth adjustably connected with the frame whereby the cylinder 10 can be effectively raised and lowered as may be desired during the use of the implement.

A further object of the invention is the provision of novel means for mounting the cylinder within the supporting frame.

A still further object of the invention is to provide a novel cultivator of the above character, which will be durable and efficient in use, one that will be simple and easy to manufacture and one which can be placed 20 upon the market at a reasonable cost.

With these and other objects in view, the invention consists in the novel construction, arrangement and formation of parts, as will be hereinafter more specifically described, 35 claimed and illustrated in the accompanying drawings, in which drawings,

Figure 1 is a top plan view of the improved cultivator,

Figure 2 is a section through the same 40 taken on the line 2—2 of Figure 1 looking in the direction of the arrows,

Figure 3 is a front elevation of the improved cultivator showing the drawing yoke in cross section,

Figure 4 is a fragmentary detail transverse section through the cultivator illustrating the means of connecting the cylinder with the supporting frame,

Figure 5 is a detail section taken on the 50 line 5—5 of Figure 4 looking in the direction of the arrows illustrating the means for adjustably mounting the cylinder on the frame,

Referring to the drawings in detail, 55 wherein similar reference characters designate corresponding parts throughout the

several views, the letter A generally indicates the improved cultivator which comprises the wheeled supporting frame B, the novel cylinder C and the novel means D for connecting the cylinder C with the wheeled frame B.

The wheeled frame B comprises an inverted U-shaped supporting member 10 which includes the transversely extending flat upper bar 11 and the depending flat side bars 12. The bars 12 adjacent to the lower ends thereof support stub axles 13 on which are rotatably mounted the ground wheels 14. The wheels are held on the stub axles 13 against displacement in any preferred way.

As shown the depending bars 12 directly above the stub axles 13 are provided with a pair of spaced vertically disposed slots 15 for a purpose, which will be hereinafter more fully described.

A U-shaped drawing yoke 16 is provided and has the rear terminals of the arms thereof mounted upon pins 17 carried by the depending side bars 12 of the U-shaped supporting member 10 and the arms of the drawing yoke 16 preferably rest upon the stub axles. As clearly shown in Figure 3 of the drawing the forward edges of the depending bars 12 of the member 10 have bolted or otherwise secured thereto guides 18 in which are fitted the arms of the drawing yoke 16. The forward end of the drawing yoke 16 has secured thereto in any desired way the draw beam or handle 19 by means of which the cultivator is drawn or pushed over a field.

The cylinder C embodies end disks 20, to the periphery of which are secured a plurality of equi-distantly spaced bars 22 which carry the cultivator teeth 23.

A supporting shaft 26 extends axially through the disks 20 and these disks are secured to the shaft for rotation therewith 100 in any preferred way.

The terminals of the shafts are rotatably mounted in bearing blocks 27 which are secured by means of bolts 28 to the means D employed for connecting the cylinder with the frame B.

The means D for connecting the cylinder with the frame B comprises spaced plates 30 and these plates are provided with a pair of slots 31 which register with the slots 15 110 in the depending bars 12 of the member 10. As clearly shown in Figure 5 of the drawing

the bearing blocks 27 are connected with the plates 30 by means of the bolts 28.

Suitable bolts 32 are extended through the paths of registering slots 15 and 31 and these bolts hold the plates 30 in any preferred adjusted position. It is obvious that the plates can be adjusted by first loosening the bolts 32 and moving the plates 30 to the desired position and then tightening the bolts.

10 By this arrangement the cylinder can be readily raised or lowered as may be desired.

From the foregoing description, it can be seen that I have provided a novel cultivator of a light construction, which is particularly 15 adapted for cultivating the putting greens of golf courses.

Changes as to details may be made without departing from the spirit or the scope of this invention, but:—

20 What I claim as new is:—

A cultivator for the purpose specified com-

prising a wheeled frame including an inverted U-shaped supporting member having a top bar and depending side bars, stub axles rigidly carried by the lower ends of the side bars and projecting outwardly therefrom, ground wheels rotatably mounted upon said stub axles, a draw yoke connected with said side bars, a transversely extending cylinder disposed in said supporting member between the side bars thereof including a supporting shaft, spaced plates slidably engaging the inner faces of the side bars, means adjustably connecting the plates with the side bars, pivotally mounted bearing blocks secured to the inner face of the side plates rotatably receiving the supporting shaft, and a plurality of spaced rows of teeth carried by the cylinder.

25 30 35 In testimony whereof I affix my signature.

CARL A. WISS.
